WEDGE-ACTUATED CLAMP FOR RESILIENT
TUBING AND THE LIKE

Joseph Hoffmann, Waterbury, Conn.

Application September 12, 1949, Serial No. 115,221

1 Claim. (Cl. 251—5)

1

This invention relates to clamps, and more particularly to a clamp having a slideable wedge-shaped clamping member which is adapted to coat with a base for adjustably gripping and compressing elongated objects such as tubes, hoses, rods, tapes, and ropes.

One object of this invention is to provide a device of the above nature in which the base comprises a frame in which the wedge-shaped member is slidably mounted.

Another object is to provide a device of the above nature in which the wedge-shaped member is provided with a slideable shoe which serves as a jaw member in opposition to the base, whereby smooth and accurate adjustment of the wedge-shaped member may be obtained, and injury to the object clamped will be avoided.

Another object is to provide a device of the above nature which may be easily operated by one hand for accurately controlling a flow of fluid in a flexible tube held in the clamp.

A further object is to provide a device of the above nature which will be simple in construction, inexpensive to manufacture, easy to install and manipulate, compact, ornamental in appearance, and very efficient and durable in use.

With these and other objects in view, there have been illustrated on the accompanying drawing two forms in which the invention may conveniently be embodied in practice.

In the drawing,

Fig. 1 is a side view of one form of the improved clamp showing a section of a tube in unclamped or open position therein.

Fig. 2 is a front view of the same.

Fig. 3 is a bottom view of the same.

Fig. 4 is a perspective view of the same, showing the parts as they would appear in clamping position for closing the tube therein.

Fig. 5 is a side view of a second form of clamp, showing a length of rope clamped therein.

Fig. 6 is a front view of the same.

Fig. 7 is a perspective view of the same showing how the clamp may be used for adjustably holding a loop of clothesline.

Referring now to the drawing in which like reference numerals denote corresponding parts throughout the several views, the numeral 10 indicates a clamp which is preferably made of sheet brass and comprises a U-shaped frame 11 having a flat base 12 and parallel flat legs 13, 14, bent outwardly at opposite edges of said base.

The legs 13, 14 have rounded outer ends 15, 16 and are provided respectively with longitudinal central slots 17, 18 which extend from the flat base 12 to narrow bearing points 19, 20 which

are formed by the outer ends of the slots. The bearing points 19, 20 are disposed at different distances from the base 12, for a purpose to be described.

5 In order to provide a variable clamping action against a length of rubber or other resilient tubing T disposed against the inner surface of the base 12, provision is made of a flat, wedge-shaped clamping member 21 which is slidably disposed in a transverse position in the slots 17, 18, and which has an outer edge 22 disposed at such an inclination that when said edge is in engagement with the outer ends 19, 20 of the slots, the inner edge 23 of said clamping member 21 will extend parallel to the flat base 12.

The opposite ends of the wedge-shaped clamping member 21 are turned at right angles thereto in order to provide rounded finger pieces 24, 25 which will facilitate manual sliding of the clamping member in the slots 17, 18, and also will serve to limit endwise movement of the clamping member and prevent its separation from the frame 11.

Thus, it will be seen that sliding of the clamping member 21 will cause the edge 23 thereof to approach or recede from the base 12, as the case may be, so that the tube T may be closed for entirely stopping a flow of fluid therethrough, or partially closed so as to restrict said flow in any desired degree. However, in order to minimize frictional resistance to the operation of the clamping member 21, provision is made of a U-shaped shoe or jaw member 26 which is preferably made of sheet brass, and which slidably embraces the edge 23 of the clamping member 21.

30 The jaw member 26 has a rounded edge 27 which is adapted to engage directly with the tube T, and also has pairs of elongated sides or guide portions 28 (Fig. 2) in slideable engagement with the inner surfaces of the legs 13, 14 for maintaining said jaw member 26 in proper operating alignment.

Operation

In use, the tube T will be inserted between the jaw member 26 and the flat base 12 when the clamp 10 is in the open (or unclamped) position illustrated in Fig. 2.

When it is desired to stop or restrict a flow of fluid in the tube T, the operator will merely press upon the finger piece 25 so as to slide the clamping member 21 to the left, thus causing the jaw member 26 to approach the base 12 and compress the tube T to the desired degree.

When the operator desires to thereafter open

the tube T so as to permit the fluid flow therein to increase, he will merely slide the clamping member 21 in the opposite direction by pressing upon the finger piece 24. It will be understood that the resiliency of the tube T, as well as any fluid pressure which may exist therein, will cause said tube to open when the clamping pressure thereon is released. The operation of sliding the clamping member 21 may be performed very conveniently, using the thumb or forefinger for pressing the finger pieces 24, or 25 while holding the clamp 10 and the tube T with other fingers of the same hand.

It will be understood that the clamp 10 may be made in any suitable size, and will be useful not only for regulating the flow of fluid in tubing, but also as a clamping means for other elongated objects. However, when the clamp is to be used for regulating a flow of fluid in a tube, the width of the flat base 12 will be made sufficient to permit the tube T to be collapsed to its fullest extent, as shown in Fig. 4, without obstruction by the legs 13, 14.

It has been found that the clamp disclosed herein is capable of very fine and accurate adjustment, inasmuch as the U-shaped jaw member 26 and the outer ends of the slots 17, 18 provide bearing surfaces which permit very smooth operation of the clamping member 21.

Second form

The second form of the invention is embodied in a clamp 29 (Figs. 5 to 7) which comprises a U-shaped frame 30 having a base 31, and parallel flat legs 32, 33 turned outwardly at opposite edges of said base.

Although the second form of the invention is generally similar to the form first described above, the base 31 has opposite downturned edge portions providing gripping edges 34, 35 which will be found particularly useful when the clamp 29 is to be employed for holding objects such as a rope R against longitudinal movement.

The legs 32, 33 have a pair of longitudinal slots 36 of different lengths, in which a flat wedge-shaped clamping member 37 is disposed.

The clamping member 37 is provided with rounded finger pieces 38, 39 at opposite ends thereof, and also is slidably embraced by a U-shaped jaw member 40 which is disposed between the legs 32, 33 and which is provided with a rounded edge 41 adapted to clamp the rope R at a point intermediate the gripping edges 34, 35.

The legs 32, 33 are extended outwardly so as to provide apertured end portions 42 which are adapted to receive the inturned ends 43, 43 of a swingable stiff wire loop 44. Thus, the loop 44 may serve as a means for holding the clamp 29 and enabling said clamp to be used for adjustably but firmly anchoring an elongated member such as the rope R.

Operation of second form

In operation, the rope R will merely be inserted

between the base 31 and the rounded edge 41 of the jaw member 40, and the finger piece 39 pressed to slide the clamping member 37 and thus cause the rope R to be securely held between the jaw member 40 and the gripping edges 34, 35.

While there have been disclosed in this specification two forms in which the invention may be embodied, it is to be understood that these forms are shown for the purpose of illustration only, and that the invention is not to be limited to the specific disclosures, but may be modified and embodied in various other forms without departing from its spirit. In short, the invention includes all the modifications and embodiments coming within the scope of the following claim.

Having thus fully described the invention, what is claimed as new, and for which it is desired to secure Letters Patent, is:

In a clamp for adjustably gripping and compressing an elongated resilient yieldable round object, a U-shaped frame of thin rigid sheet material comprising a wide flat base and a pair of integral parallel legs perpendicular to said base, said legs having narrow central slots of unequal lengths being formed perpendicular to said base and extending from points adjacent said base, said legs having rounded outer ends, the ends of said slots remote from the base providing bearing points, a flat thin elongated wedge shaped member of rigid thin sheet material slidably fitted within said slots, the wedge shaped member having an outer edge engaging said bearing points in such manner that the inner edge of the wedge shaped member is in opposing parallel relationship with the base in all positions of the wedge shaped member, the outer ends of said wedge shaped member having rounded finger pieces bent over parallel to said legs, a U-shaped follower jaw of thin rigid sheet material fitted about the inner edge of said wedge member and having its side edges abutting the inner sides of said parallel legs, said jaw having a rounded looped edge for engagement with said round object.

JOSEPH HOFFMANN.
